TUBE ROLLING APPARATUS

Robert K. Hopkins, St. George, Staten Island,
N. Y., assignor to The M. W. Kellogg Company,
New York, N. Y., a Corporation of Delaware

Application September 12, 1930
Serial No. 481,392

10 Claims.

(Cl. 80—5)

This invention relates to the manufacture of seamless tubes and hollow bodies particularly by internal and external rolling.

Ordinarily in rolling seamless tubes on a cylinder rolling mill a hollow ingot which has previously been heated to the proper forging temperature is positioned on a main roll and held in a central position by auxiliary centering rolls adjacent the main roll. Another roll smaller than the main roll is passed through the hole in the hollow ingot and positioned for the rolling operation adjacent the inner wall of the ingot directly opposite the point where the outer main roll contacts the ingot. In other words, the rolls are spaced apart by the ingot wall.

The main supporting external roll and the internal roll are then rotated and the axes of the two rolls are displaced toward each other thus making an impression in the ingot corresponding to the draft in a normal rolling operation. As the ingot revolves with the reduction taking place, the hot steel is mechanically worked and the circumference of the ingot increases in length thus increasing the diameter of the ingot. This operation is continued until the ingot has reached the desired size.

The difficulty in rolling a cylinder of this character is that it is practically impossible to keep all fibers along the length of the ingot elongating at the same rate and unless this is done the finished tube will not be of true cylindrical shape. If more rolling is done in the center of the tube than at the ends it will assume a barrel shape due to greater elongation at this point and conversely if more rolling is done at the two ends than in the middle greater elongation occurs at these points resulting in a tube having a bell mouthed shape. In the ideal rolling process the fibers elongate at the same rate resulting in a tube of true cylindrical form. However, if the internal and external rolls are truly cylindrical a tube during the rolling process would tend to develop a bell mouthed shape due to the fact that the rolls, and particularly the small internal roll, would deflect an appreciable amount resulting in less rolling pressure at the center of the tube than at the ends.

The rolling pressure along the ingot may be regulated by using one or more rolls which have been machined so as to have normally a camber, that is, a curvature upwards from the point of greatest pressure with the tube which is the correct amount of camber to suit the rolling pressure. Theoretically, this camber could be calculated

and if all ingots were homogeneous, a certain calculated camber on one or more of the rolls together with the application of certain definite and constant rolling pressures would result in a perfect seamless tube. This, however, is an ideal condition and one which cannot be expected in normal practice for the reason that all ingots are not truly homogeneous, and also for the reason that the temperature at which rolling is carried out, contributes another factor which plays an important part in the deflection of the rolls.

An object of this invention is to roll a hollow ingot to form a seamless tube or cylinder in such a manner that the fibers elongate simultaneously and at the same rate.

Another object of this invention is to obtain a control for this rolling operation in order that irregularities formed during rolling may be compensated for and a true cylinder obtained.

Still another object of the invention is to vary the section at which the greatest rolling pressure is applied to an ingot during the rolling process.

I have found that by using a cambered internal roll and by regulating the rolling pressure, that is, the pressure of the large external roll against the relatively small internal roll, the flexure of the internal roll may be controlled at will so that if desired the greatest pressure may be applied at the center of the tube by applying a pressure which is not quite sufficient to flex all the camber from the roll. Constant pressure over the entire line of rolling contact may be maintained by applying sufficient pressure so that all of the camber is flexed from the roll; in other words, the element of the roll at the line of contact with the tube is a straight line. A third condition may be obtained, namely, one in which the greatest rolling pressure is applied to the ends of the tube by increasing the pressure until it is more than sufficient to flex all the camber from the internal roll. The external roll may also be cambered if desired.

Still another feature of the invention resides in canting the ingot to be rolled with respect to the cambered roll so that the point of greatest pressure can be regulated to any position between the ends of the tube.

Other objects and features of my invention will be apparent and a better understanding thereof obtained by reading the following description together with the accompanying drawings of which:

Figure 1 shows a rolling mill in which a cambered roll is employed, the internal roll having its normal camber.

Figure 2 is a transverse section through Figure 1 showing the relative positions of the rolls together with the auxiliary positioning rolls.

Figures 3 to 5 show conditions of the rolls during different degrees of flexure.

Figure 6 shows one method of canting the roll and tube for varying the point of greatest rolling pressure on the tube.

Referring to the drawings, a rolling mill is shown having a base 10 with suitable standards 11 to support the bearings of the rolls 12 and 13. The bearings 14 are adapted for vertical movement in the standards 11 and the rate and amount of this vertical movement is controlled by the screws 15. Suitable means, not shown, but preferably power driven, are provided for operating the screws 15 by means of which the rolling pressure on the tube is controlled as will be evident hereafter. The bearings 16 for the roll 13 are of the ball and socket type in order that this roll may be flexed without undue strain on the journals of the roll.

The bearings 16 are such that the roll 13 may be easily withdrawn for the insertion of the hollow billet 17 which is to be worked. In Figure 2 a pair of auxiliary rolls are shown which support the hollow billet 17 centrally on the roll 12 and means are provided associated with the rolls 18 to permit them to swing outwardly to accommodate for the increase in the radius of curvature of the hollow billet from the rolling process.

During the rolling process, of course, the same pressure is exerted on the roll 12 as on the roll 13 and consequently there is the same tendency for each to flex, but where the rolls are so different in size as those in the modification shown, the flexing of the large roll 12 may be neglected and that only of the roll 13 considered. Of course, the invention is not limited to a case where the one roll is flexed, but is sufficiently broad to include cases where either or both are flexed. Since in the modification shown, however, the flexure of the roll 13 need only be considered, this roll has been shown with a cambered surface, that is, one in which the center has a greater transverse cross-sectional area than the two ends. Suitable power means are provided for driving the rolls 12 and 13 at suitable speed, but as the driving mechanism has no concern with my invention it has not been shown. As mentioned heretofore, the rolling pressure upon the hollow billet is regulated by the screws 15 which bear against the bearings 14 and sufficient regulation is obtained by means of these screws 15 so that the rolling pressure upon the billet may be varied from zero to an amount which is sufficient to flex the roll to a condition where the cambered contour of the surface has been reversed, as shown in Figure 5. Various intermediate stages are shown in Figures 3 to 5. Thus, Figure 3 shows a condition where the roll 13 is slightly flexed but wherein a slight camber of the contacting element of the roll is retained. Figure 4 shows a condition of the roll 13 where sufficient pressure has been applied to straighten the camber so that the pressure on the billet is uniform. Figure 5 shows a condition where still greater pressure has been applied which is more than sufficient to bend the camber out of the roll and wherein the greatest pressure is applied to the billet at the ends.

The rolling operation is carried out as follows: The roll 13 is withdrawn and the hot ingot positioned on the roll 12 supported by the auxiliary rolls 18. The roll 13 is then inserted in the hole

of the hollow billet and firmly secured in its bearings. The rolling operation is then started with the roll flexed to the position shown in Figure 4, that is, with the pressure on the roll 13 regulated to give a straight line rolling contact. This insures even pressure on the ingot. Rolling with this pressure is continued until it is noticed that the tube or billet is not rolling in a truly cylindrical form, in which case the control is regulated to correct the rolling condition, that is, if it be found that the tube is becoming barrel shaped due to the greater elongation of the tube fibres at the center of the roll, the pressure is increased until the roll 12 is flexed to the condition shown in Figure 5 and the rolling then continued until the tube again assumes a true cylindrical shape at which time the pressure may be decreased so that the roll 12 again assumes the straight rolling condition as shown in Figure 4. On the other hand, if the rolling is proceeding so that the tube is becoming bell mouth shaped at the ends, the pressure on the bearings 14 may be decreased by means of the screws 15 until the roll 12 assumes the shape shown in Figure 3, that is, having a slight camber existing which is sufficient to apply the greatest pressure at the middle of the roll. Thus by properly operating the machine, in accordance with the invention, a true cylindrical seamless tube or cylinder may be manufactured.

Another embodiment of the invention is shown in Figure 6. This embodiment is particularly desirable where long lengths of tubes are to be rolled and where difficulties may develop which would be hard to correct unless it were possible to shift the point of greatest pressure along the length of the tube. By canting either or both of the rolls the normal to the surface of the cambered roll at the point of contact with the tube is shifted at will along the length of the tube. This normal point is also the point of greatest pressure. In the modification shown in Figure 6, the main or lower roll 12 is the one which is adjustable. The normal position of the roll is shown in full lines while the dotted lines show the roll 12 in one of its canted positions, that is, the axis of the roll has been shifted from its position S—S to the position S'—S'. Of course, this is only one position which the roll 12 may assume as it is also possible to shift the roll in the other direction, so that the point of greatest pressure may be adjusted to any position intermediate the ends of the tube.

In describing this invention several embodiments have been shown but many others will at once suggest themselves to those skilled in the art within the spirit of the invention which is to be limited therefore only by the prior art and the scope of the appended claims.

I claim:

1. A machine for the manufacture of tubes or hollow bodies by internal and external rolling comprising a main roll, a second roll having a normally cambered surface and means for changing the symmetry of the cambered surface during the rolling process.

2. A machine for the manufacture of tubes or hollow bodies by internal and external rolling, comprising a main roll, a second roll having a normally cambered surface and means for changing the said cambered surface adjacent the element being rolled during the rolling process.

3. A machine for the manufacture of tubes or hollow bodies by internal and external rolling

- comprising a main roll, a second roll having a normally cambered surface, and means for dis-
placing said main roll with reference to said sec-
ond roll to effect a change in the symmetry of the
5 said second roll during the rolling process.
4. A machine for the manufacture of tubes or
hollow bodies by internal and external rolling
comprising a main roll, a second roll having a
normally cambered surface, bearings for said
10 main roll and means for exerting pressure on
the said main roll during the rolling process to
effect a change in the symmetry of said second
cambered roll.
5. A machine for the manufacture of tubes or
15 hollow bodies by internal and external rolling
comprising a main roll for supporting the tube
blank and means effecting constant rolling pres-
sure along an element of said blank, said means
comprising a normally cambered roll adapted to
20 be flexed so that the element of the cambered
roll contacting with the tube blank is a straight
line.
6. A machine for the manufacture of tubes or
hollow bodies comprising a roll adapted to sup-
25 port a tube blank, a cambered roll adapted to
contact with said tube internally, means for ex-
erting rolling pressure on said tube and for flex-
ing said cambered roll whereby the curve at the
line of contact of said cambered roll may be
diminished or reversed.
7. A machine for the manufacture of tubes or
hollow bodies comprising a main roll and a cam-
bered roll and means for varying the angular
relation between the axes of said rolls. 80
8. A machine for the manufacture of tubes or
hollow bodies comprising a main roll and a cam-
bered roll and means for canting the main roll
with reference to the axis of the cambered roll. 85
9. A machine for the manufacture of tubes or
hollow bodies comprising a main roll for sup-
porting a hollow tube blank, a cambered roll
positioned internally of the tube blank, between
which rolls the tube is adapted to be rolled, and
means for varying the angular relation between
the axis of the cambered roll and the axis of the
tube blank. 90
10. A machine for the manufacture of tubes or
hollow bodies comprising a main roll for sup-
porting a hollow tube blank, a cambered roll
positioned internally of the tube blank and
adapted to apply a rolling pressure to the tube
together with the main roll and means for cant-
ing the tube blank with reference to the axis of 100
the cambered roll. 95
